Primary Examiner — Messina L Smith

CLAIM

The ornamental design for a beauty instrument, as shown and described.

DESCRIPTION

FIG. 1 is a front and top perspective view of a beauty instrument, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the beauty instrument, shown in an environment of use.

The broken line showing of the base and heads in FIG. 9 depicts environment and forms no part of the claimed design. All other broken lines depict portions of the beauty instrument that form no part of the claimed design.

1 Claim, 9 Drawing Sheets
